UNITED STATES PATENT OFFICE.

DOCTOR CHESTER MAULDIN, OF LONE OAK, TEXAS.

RAILWAY-RAIL JOINT.

SPECIFICATION forming part of Letters Patent No. 600,793, dated March 15, 1898.

Application filed September 20, 1897. Serial No. 652,358. (No model.)

To all whom it may concern:

Be it known that I, DOCTOR CHESTER MAULDIN, a citizen of the United States, and a resident of Lone Oak, in the county of Hunt and State of Texas, have invented certain new and useful Improvements in Railway-Rail Joints; and I do hereby declare that the following is a full, clear, and exact description of the invention, which will enable others skilled in the art to which it appertains to make and use the same, reference being had to the accompanying drawings, which form a part of this specification.

My invention relates to joints for connecting ends of railway-rails; and its object is to provide an improved construction of the same by which the rails may be securely connected and prevented from spreading, and dispensing with the ordinary fish-plates now commonly employed.

The invention consists, essentially, in a metal plate adapted to rest upon an ordinary railway-tie, formed near each end with two upwardly-projecting lugs beveled or inclined at their adjoining ends and formed near their inner edges with a series of holes, which are alined with corresponding holes in the plate, in combination with the tie, the rails engaging with said lugs, and with spikes passing through said holes, as hereinafter fully described and claimed.

In the accompanying drawings, Figure 1 is a sectional view taken transversely across a railway-track, showing the rails and tie provided with my improvements. Fig. 2 is a plan view of the same. Fig. 3 is a perspective view of the metal joint. Fig. 4 is a perspective view of the ends of two railroad-rails.

In the said drawings the reference-numeral 1 designates a wooden railway-tie, and 2 the joint. This joint consists of a metal plate formed near each end with two lugs arranged in pairs, with a space between the lugs of each pair. The inner or adjoining sides of these lugs are beveled at 3 to correspond with the base 4 of the rails 5. These lugs at their upper ends are formed with a number of holes 6, and the plate is formed with corre-

sponding holes 7 for the passage of spikes 8, which also pass through the base of the rails. 50 As will be seen by referring to Fig. 4, one end of the rails 5 is formed with slots 9 in the upper end of the base and with holes 10 at the inner end to receive the spikes. The other end of the rails is formed with tongues 55 12 and holes 13. In practice the tongues of one rail will fit in the slots of the adjoining rail, and the holes 10 and 13 will be alined with the spike-holes of the lugs, so that the spikes passing through the lugs will also pass 60 through the holes in the rails. The holes 10 and 13, as will be seen, are elongated to permit of expansion and contraction of the rails.

The rails should fit loosely enough between the lugs to enable them to be readily withdrawn when required, and the plate or joints are to be secured to the ties at the meeting ends of the rails.

Having thus fully described my invention, what I claim is—

1. The combination with the wooden tie, of the joint consisting of the metal plate having formed integral therewith near each end two lugs, the inner or adjoining sides of which are beveled and formed with holes and the 75 said plate formed with coinciding holes, the rails fitting between said lugs and the spikes, substantially as described.

2. The combination with the wooden tie and the joint consisting of the metal plate 80 having formed integral therewith near each end two lugs, the inner or adjoining sides of which are beveled and formed with holes and the said plates formed with coinciding holes, of the rails fitting between said lugs formed 85 at their adjoining ends with interlocking tongues and stops and holes and the spikes passing through said lugs, plate and rails, substantially as described.

In testimony that I claim the foregoing as 90 my own I have hereunto affixed my signature in presence of two witnesses.

DOCTOR CHESTER MAULDIN.

Witnesses:

C. J. HUNDLY,
M. E. MACKEY.
